UNITED STATES PATENT OFFICE

FRANK J. KAPS, OF NEW YORK, N. Y.

BOTTLE CLOSURE

Application filed May 31, 1930. Serial No. 457,776.

This invention relates to new and useful improvements in a bottle closure.

The invention has for an object the provision of a device of the class mentioned which is of simple durable construction, dependable in use and efficient in action, and which can be manufactured and sold at a reasonable cost.

The invention proposes a bottle closure including a bottle neck cap having a large base portion with a small upper threaded portion and a conical top formed with a pin-hole aperture, a cover for engagement on said cap formed with a large base engageable on said large base portion and an interior small threaded top engageable on said small upper threaded portion, and a sealing member supported in said cover for engagement against said conical cap top and against the pinhole aperture for preventing evaporation of contained fluid.

The invention also proposes a means for adjusting the sealing member to close the pinhole aperture in the cap member when the cover is placed loosely upon the cap and not screwed in place.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a side elevational view of a device constructed according to this invention.

Fig. 2 is a fragmentary enlarged vertical sectional view of the cover per se.

Fig. 3 is a fragmentary side elevational view of the bottle neck cap shown upon a bottle without the cover.

Fig. 4 is a plan view of Fig. 3.

Fig. 5 is a vertical sectional view of Fig. 3.

Fig. 6 is a view similar to Fig. 3, but showing the cover in place.

Fig. 7 is a view similar to Fig. 6, but illustrating a modification.

The bottle closure comprises a bottle neck cap 10 having a large base portion 11 with

a small upper threaded portion 12 and a conical top 13 formed with a pinhole aperture 14, a cover 15 for engagement on said cap 10 and formed with a large base portion 16 for engagement upon the base portion 11 of the cap and an interior small threaded portion 17 for engagement upon the threaded portion 12, and a sealing member 18 supported in said cover 15 for engagement against said conical cap top 13 and against the pinhole 14 for preventing evaporation of the contained liquid.

The bottle closure is shown upon a bottle 19 of any design or construction. It is particularly intended that this bottle hold perfume or any volatile liquid. The neck 20 of the bottle is formed with threads 21 formed in the large base portion 11. The cap 10 should preferably be made from sheet metal and highly polished for aiding to its appearance. The lower edge 22 is shown turned up so as to form a finished edge in the cap. A rim portion 23 is formed directly above the threads 21 and is provided with a plurality of serrations as may be seen from an inspection of Fig. 3 for manual gripping.

The curved portion 24 connects the rim 23 with the threaded portion 12. A washer 25 is positioned within the cap 10 and rests against the inside of the curved portion 24 and is engageable against the top of the neck 20 of the bottle as shown in Fig. 5. This forms a tight connection to prevent leakage from the interior of the bottle and the inner sides of the threads 21. The conical top 13 is integral with the top of the threads 12 and may be formed by spinning or drawn under the action of a die. The pinhole 14 within the conical top 13 is located at its center and is of small diameter so that but small quantities of the contained liquid may be discharged from the bottle at a time.

The cover 15 is made from sheet brass by spinning or stamping and is shown to consist of two sections, namely an outer section 26 and an inner section 27. The bottom edge 28' of the outer section is flared as clearly shown in Fig. 2 and the bottom edge of the inner section is turned upward around the

flared edge 28' and clamped in place for firmly securing both sections together. The outer section 26 consists of a cylindrical portion 29 terminating at the bottom in said flared portion 28' and connecting at the top with an enlarged hollow head 30, which is slightly convexed at the top 31. A projection 32 extends downwards from the central portion of the top side of the head 31 and slightly bows down the sealing member 18 as may be observed in Fig. 2. It is calculated that when the cover is engaged upon the cap, the bowed down portion of the sealing member is tightly pressed into the pinhole 14. The inner section 28 is arranged coaxially within the section 29 and consists of a cylindrical portion 33 connected with the said upturned edge which encircles the flared edge 28' of the outer section, and connects with a reducer central portion 28 which in turn connects with the said threaded portion 17. A hollow space 34 is thus provided between the sections causing the cover to be quite light. The top of the threaded portion 17 is opened and is slightly dug into the sealing member 18 so as to retain the sealing member against free motion within the cover. The sealing member is arranged flat against the inside of the top portion 31 of the cover and between the top edge of the threaded portion 17 of the inner section. This sealing member may be of cork, rubber and the like.

In Fig. 7 a means has been provided for adjusting the sealing member to close the pinhole and the cap member when the cover is placed loosely upon the cap and not screwed in place. This means comprises a flexible sealing member 18' engaged over the open top of the threaded portion 17 and secured upon the exterior of the threaded portion 17 by a wire 35 formed in a circle and having its ends twisted together. A spring 36 is attached upon the bottom of the top portion 31 of the outer section 26 and has a curved front end 37 capable of being flattened out. The normal position of the spring is that shown in Fig. 7 in which the curved front end 37 forces the sealing member 18 downwards so that it may engage against the pinhole 14 even though the cover is not screwed in place on the cap. When the cover is screwed down in place the spring 37 flattens out to allow such screwing.

The operation of the device may be understood by first assuming it in the condition as shown in Fig. 4, that is, with the cover tightly screwed in place upon the cap. In this condition the sealing member acts against the pinhole 14 so as to prevent the leakage of fumes or liquid from the interior of the container to the atmosphere. The threads 17 engaging upon the threads 12 form an air packing and this air packing is supplemented by the cylindrical portion 27 of the inner section of the cover engaging

against the sides of the threads 11. The escape of fumes necessarily must pass through a large distance, that is, around the spiral of the threads 11 before escape is possible and this tends to minimize such leakage. The large portion 30 of the outer section of the cover permits large mechanical advantage over the small threaded portion 17 of the inner section so that removing of the cover is easy.

When the cover is removed the liquid from within the container may be discharged through the pinhole by shaking. If the cover is loosely placed upon the cap of the bottle without screwing it down, there is a certain amount of sealing produced in that the overhanging sides 27 engage against the outsides of the threads 11 forming an air packing as before explained. In addition, the top of the thread portion 12 engages against the bottom of the threads 17 producing some sealing effect, finally the third sealing effect is obtained at the flared edges 28' which engages the bottle 19 after the cover is turned into place.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. A bottle closure, comprising a bottle neck cap having a large base portion adaptable to a bottle neck and a small upper threaded portion and a conical top with a pinhole aperture, a cover for engagement on said cap formed with a large base engageable over said large base portion of the cap and an interior small threaded top engageable over the said upper threaded portion of the cap, and a sealing member supported on said cover for engagement against said conical cap top and against the pinhole aperture for preventing evaporation of liquid within a bottle provided with the closure.

2. A bottle closure, comprising a bottle neck cap having a larger base portion adaptable to a bottle neck and a small upper threaded portion and a conical top with a pinhole aperture, a cover for engagement on said cap formed with a large base engageable over said large base portion of the cap and an interior small threaded top engageable over the said upper threaded portion of the cap, and a sealing member supported on said cover for engagement against said conical cap top and against the pinhole aperture for preventing evaporation of liquid within a bottle provided with the closure, the bottom edge of said cap being turned upwards so as to form a finished edge.

3. A bottle closure, comprising a bottle neck cap having a large base portion adaptable to a bottle neck and a small upper threaded portion and a conical top with a pinhole aperture, a cover for engagement on said cap formed with a large base engageable over said large base portion of the cap and an interior small threaded top engageable over the said upper threaded portion of the cap, and a sealing member supported on said cover for engagement against said conical cap top and against the pinhole aperture for preventing evaporation of liquid within a bottle provided with the closure, said cap having a serrated portion disposed between said large base portion and the threaded portion providing manual gripping of the cap. 70
4. A bottle closure, comprising a bottle neck cap having a large base portion adaptable to a bottle neck and a small upper threaded portion and a conical top with a pinhole aperture, a cover for engagement on said cap formed with a large base engageable over said large base portion of the cap and an interior small threaded top engageable over the said upper threaded portion of the cap, and a sealing member supported on said cover for engagement against said conical cap top and against the pinhole aperture for preventing evaporation of liquid within a bottle provided with the closure, said cover being formed of two sections connected together and having portions spaced with each other presenting a hollow to result in little weight. 75
5. A bottle closure, comprising a bottle neck cap having a large base portion adaptable to a bottle neck and a small upper threaded portion and a conical top with a pinhole aperture, a cover for engagement on said cap formed with a large base engageable over said large base portion of the cap and an interior small threaded top engageable over the said upper threaded portion of the cap, a sealing member supported on said cover for engagement against said conical cap top and against the pinhole aperture for preventing evaporation of liquid within a bottle provided with the closure, and means for adjusting the sealing member to close the pinhole in the cap when the cover is placed loosely upon the cap and not screwed in place, comprising means for supporting said sealing member, and a spring attached on said cover and extending beneath said sealing member and normally urging said sealing member into an extended position. 80
6. A bottle closure, comprising a bottle neck cap having a large base portion adaptable to a bottle neck and a small upper threaded portion and a conical top with a pinhole aperture, a cover for engagement on said cap formed with a large base engageable over said large base portion of the cap and an interior small threaded top engageable over the said upper threaded portion of the cap, a sealing member supported on said cover for engagement against said conical cap top and against the pinhole aperture for preventing evaporation of liquid within a bottle provided with the closure, and means for adjusting the sealing member to close the pinhole in the cap when the cover is placed loosely upon the cap and not screwed in place, comprising a wire formed in a circle around said sealing member and having its ends twisted together, and said wire securing said sealing member to the said interior small threaded top. 85
7. A bottle closure, comprising a bottle neck cap having a large base portion with a small upper threaded portion and a conical top with a pinhole aperture, a cover for engagement on said cap formed with a large base engageable over said large base portion of the cap and an interior small threaded top engageable over the said upper threaded portion of the cap, a sealing member supported on said cover for engagement against said conical cap top and against the pinhole aperture for preventing evaporation of liquid within a bottle provided with the closure, and means for adjusting the sealing member to close the pinhole in the cap when the cover is placed loosely upon the cap and not screwed in place. 90
8. A bottle closure, comprising a bottle neck cap having a large base portion with a small upper threaded portion and a conical top with a pinhole aperture, a cover for engagement on said cap formed with a large base engageable over said large base portion of the cap and an interior small threaded top engageable over the said upper threaded portion of the cap, a sealing member supported on said cover for engagement against said conical cap top and against the pinhole aperture for preventing evaporation of liquid within a bottle provided with the closure, and means for adjusting the sealing member to close the pinhole in the cap when the cover is placed loosely upon the cap and not screwed in place, comprising a spring attached on said cover and extending beneath said sealing member and normally urging said sealing member into an extended position. 95
